UNITED STATES PATENT OFFICE.

WALTER F. KOKEN, OF ST. LOUIS, MISSOURI.

DESIGN FOR A BARBER POLE.

Application filed March 24, 1922. Serial No. 1,373. Term of patent 14 years.

To all whom it may concern:

Be it known that I, WALTER F. KOKEN, new design.
a citizen of the United States, residing at St. Louis, Missouri, have invented a certain specification, reference being had to the accompanying drawing, forming part thereof.

The figure is a side elevational view of my

I claim:

The ornamental design for a barber pole,
new, original, and ornamental Design for a as shown.

WALTER F. KOKEN.
